Sterling; Daniel Peter, Dosage Packaging For Washing Agents, Design U.S. Appl. No. 29/652,552, filed Sep. 17, 2020, United States.

Primary Examiner — Jennifer Rivard

(74) *Attorney, Agent, or Firm* — Bojuan Deng

(57) **CLAIM**

The ornamental design for dosage packaging for washing agents, as shown and described.

DESCRIPTION

FIG. 1 is a top perspective view of a first dosage packaging for washing agents embodying the new design;

FIG. 2 is a top side view thereof;

FIG. 3 is a bottom side view thereof;

FIG. 4 is a front side view thereof;

FIG. 5 is a back-side view thereof;

FIG. 6 is a right-side view thereof;

FIG. 7 is a left-side view thereof;

FIG. 8 is a top perspective view of a second dosage packaging for washing agents embodying the new design;

FIG. 9 is a top side view thereof;

FIG. 10 is a bottom side view thereof;

FIG. 11 is a front side view thereof;

FIG. 12 is a back-side view thereof;

FIG. 13 is a right-side view thereof;

FIG. 14 is a left-side view thereof;

FIG. 15 is a top perspective view of a third dosage packaging for washing agents embodying the new design;

FIG. 16 is a top side view thereof;

FIG. 17 is a bottom side view thereof;

FIG. 18 is a front side view thereof;

FIG. 19 is a back-side view thereof;

FIG. 20 is a right-side view thereof;

FIG. 21 is a left-side view thereof;

FIG. 22 is a top perspective view of a fourth dosage packaging for washing agents embodying the new design;

FIG. 23 is a top side view thereof;

FIG. 24 is a bottom side view thereof;

FIG. 25 is a front side view thereof;

FIG. 26 is a back-side view thereof;

FIG. 27 is a right-side view thereof; and,

FIG. 28 is a left-side view thereof.
